BRUSH AND METHOD OF MAKING THE
SAMEErnest B. Wright, Jr., Montclair, and George N.
Jacob, Jr., Belleville, N. J.

Application July 29, 1933, Serial No. 682,736

12 Claims. (Cl. 300—21)

This invention relates to brushes and methods of manufacturing the same, and aims generally to provide a durable high grade brush of good appearance made by a simple and inexpensive method which does not require the use of special molds.

The production at reasonable cost of good brushes having tufts of single length bristles has been a long recognized want in the brush industry, and many efforts have been made to meet this want. The methods and means heretofore employed for anchoring the bristles in the face portion of the brush body have, however, been either comparatively costly or unsatisfactory in results.

15 The present invention provides an improved brush in which tufts of single length bristles and the individual bristles of each tuft are securely held, and a method of manufacturing such brushes at comparatively low cost in respect to equipment, labor and materials.

20 The invention comprises a brush having spaced tufts of bristles the ends of which are embedded in a layer of solidified binding material which forms the face of the brush body, the bristles of each embedded tuft end extending in the general direction of the length of the tuft but being spaced apart, and the binding material extending into the embedded ends of the tufts between individual bristles thereof so that the bristles 25 are individually gripped by the binding material and each embedded tuft end is securely anchored in the facing layer of binding material; and a method wherein the bristle tufts are positioned in desired spaced arrangement and constricted 30 at a point spaced from their inner ends a distance substantially greater than the depth to which the ends of the tufts are to be embedded in the binding material, and while the tufts are so relatively positioned and constricted, the inner ends of the 35 tufts are immersed in a layer of liquid binding material which, while the tuft ends are held in position therein, is solidified to form the facing layer of the brush. Constricting the tufts at a 40 point spaced from their inner ends a distance greater than the depth to which the ends of the tufts are to be embedded in the binding material causes the bristles of these end portions of the tufts to diverge so as to be spaced apart for a 45 distance from their ends greater than the depth to which they are to be embedded in the layer of binding material, and thus affords opportunity for the binding material to enter and grip the individual bristles. Other features of the brush 50 and of the method are described hereinafter and

the invention is particularly pointed out in the claims.

The invention in its broader aspect is not limited to brushes having the bristles arranged in spaced tufts, but includes on its product side, and the method extends to the making of, brushes in which the bristles are arranged in spaced rows or other groups or assemblages. 5

The steps of the method can be carried out by the use of relatively unskilled labor, and the brushes can be produced in large quantities at a minimum of expense for equipment, and particularly without any substantial outlay for special equipment which cannot be used for general purposes in a brush making factory. No pressure 15 molding devices or closed molds are needed.

In the accompanying drawings:—

Fig. 1 represents diagrammatically a jouncing machine and hopper arrangement for accomplishing the insertion of the bristles in controlled 20 form into a template;

Fig. 2 represents the jouncing machine and hopper shown in Fig. 1 as rearranged to separate out loose bristles from between the tufts;

Fig. 3 illustrates the template with inserted 25 bristle tufts;

Fig. 4 is a view in section showing an assembly of a back or filler block with a shell or casing member to form a sink or well in which a rubber composition solution or other suitable binder material is deposited in liquid condition; 30

Fig. 5 shows the manner of arranging the assembly shown in Fig. 3 with the assembly shown in Fig. 4;

Fig. 6 is a view of a finished brush; 35

Fig. 7 is a fragmentary view in cross-section of the brush, illustrating the character of union between the bristles and the facing layer of the brush;

Fig. 8 is a sectional view taken on line 8—8 40 of Fig. 9 showing bristles held and constricted as they may be for making a brush of which the bristles are arranged in spaced rows;

Fig. 9 is a section taken on line 9—9 of Fig. 8 and showing the root ends of the bristles inserted 45 in the layer of binding material of the brush body and indicating by dotted lines the position taken by the bristles when the constricting means is removed; and

Fig. 10 shows a template which may be used 50 in making a brush such as illustrated by Fig. 9.

The drawings show a paint stippling brush of preferred form according to the invention. Referring especially to Figs. 5, 6 and 7, the brush body comprises a back or filler block 10, which for 55

lightness is preferably made of a light wood such as balsa wood, a facing layer 11 of solidified binding material, and, in the particular construction shown, a shell or casing 12 of metal or 5 other suitable material, which covers the back and edges of the filler block 10 and the edges of the facing layer 11. The shell 12 may be cast or otherwise formed, and may have a narrow inwardly extending flange 13 at its edge which in 10 the completed brush extends slightly over the surface of the facing layer 11. The facing layer 11 is, as hereinafter explained, solidified in place and becomes thereby suitably adherent to the face of the filler block 10, or it may itself entirely fill the metal shell or casing as in the brush 15 shown in Fig. 9. Additional means, such as the screws commonly employed for securing face plates of brushes, may be resorted to for more firmly securing the facing layer, but the use of 20 such additional means is not necessary when the brush body comprises a shell or casing as in the construction shown.

The embedded end, or root, portions of the tufts most desirably extend completely through the 25 facing layer 11 and abut against the filler block 10, and the bristles of each embedded tuft root portion are spaced apart for their whole embedded length, and binding material extends into the embedded ends of the tufts between individual 30 bristles thereof, so that, as stated, the bristles are individually gripped by the binding material and each embedded tuft end is securely anchored in the facing layer. In addition to being so spaced apart, the bristles of the embedded tuft 35 ends diverge slightly from the outer surface of the facing layer inward. This affords additional security in the anchoring of the tufts in the facing layer. The filler block and the extending side portion of the casing form a sink or well 14 in 40 which the binding material is solidified to form the facing layer 11 as hereinafter described.

In making a brush in accordance with the method of the invention and as now considered best, the procedure is as follows:—The required 45 number of tufts of single length bristles, that is, bristles of the length of the tufts, are formed and arranged in the spaced relation which they are to have in the brush, and each tuft is tightly gripped, or constricted, at a point spaced from 50 its inner end a distance substantially greater than the depth to which that end of the tuft is to be embedded in the facing layer of the brush body. This is accomplished most desirably by filling the bristles into a perforated tuft holding 55 plate, or template, having perforations of a size to hold tightly tufts of the desired size and spaced and arranged according to the desired spacing and arrangement of the tufts in the completed brush. The template may be a comparatively 60 thin plate, as shown at 15 in Figs. 3 and 5, of metal or other suitable rigid material. A metal plate of about one-quarter inch thickness has been found suitable. The tuft-forming bristles may be grouped and entered into the perforations of the template in any suitable manner, but the bristles should be packed tightly in the perforations and the tufts should extend through the plate a uniform distance substantially greater 65 than the depth to which the ends of the tufts are to be embedded in the facing layer of the brush body. The bristles being tightly packed in the perforations of the template and thus constricted, the extending end portions of the tufts will expand and take an outwardly flaring form, so that 70 the bristles of each tuft root end portion will be

spaced apart for a distance from their ends greater than the depth to which they are to be immersed in the binding material.

The template or tuft holder 15 is most conveniently "filled" by the well-known jouncing 5 method. For this purpose a jouncing machine such as indicated by Fig. 1 may be used. The template 15 is positioned at the bottom of a hopper 16 set on spacing blocks 17 on the jouncing table 18 of the machine and held in position 10 by dowel pins 19, the template being spaced from the top of the table a distance equal to the length to which it is desired that the bristle tufts shall project through the template. The jouncing of the table 18 is effected by an eccentric 20 on a rotating shaft 21, the eccentric giving an up and down movement to a plate 22 which is guided by the legs 23 of a stationary table 24. The jouncing table 18 is normally supported on the stationary table 24 by means of shouldered tappets 25, reduced lower ends of which extend through openings in the table 24 and project beneath the table to be engaged by an adjustable jouncing bar 26 carried by the plate 22, so that when the shaft 21 rotates the jouncing bar 26 will engage the 25 tappets 25 at each reciprocation and thereby jounce the table 18. The bristles are placed in the hopper standing vertically so that they may be jounced into and through the perforations in the template. The jouncing operation is carried on for several minutes or until the perforations of the template become tightly packed with the bristles, which will extend through the template to a uniform extent determined by the distance 30 that the template is set above the top of the 35 jouncing table 18.

After the tufts have been thus formed of bristles packed tightly in the perforations of the template, the hopper and template are lifted from the jouncing table, and the assembled template 40 and hopper may then be inverted and placed on the same or another jouncing mechanism and lightly jounced to free the tufts projecting into the hopper from the mass of loose bristles which have been left between the tufts. 45 Most desirably, before this second jouncing operation the ends of the shorter projecting outwardly flaring portions 30 of the tufts are immersed in or bathed with a suitable solidifiable adhesive or binding material such as a suitable 50 rubber cement or bakelite cement to hold the ends of the bristles spaced apart and thereby insure against loss or displacement of individual bristles and minimize movement of the tufts in the template in the second jouncing operation. 55 The particular material used will depend on the binding material used for the main portion of the facing layer of the brush.

The template is most desirably counter-sunk at the entrance side of its perforations, as indicated 60 at 28, thereby facilitating the introduction of the bristles into the perforations. Inasmuch as the template does not become part of the completed brush, such counter-sinking is not objectionable as it would be if the perforated plate were to 65 become the face of the brush. When the plate serves as the face of the brush, it is undesirable for sanitary reasons to have its perforations counter-sunk, as dirt lodged around the base of the bristles is not then readily removed. In the 70 brush of the present invention, of which the template forms no part, the facing layer of binding material has a clean, smooth surface which fits closely against and around the base of the tufts.

A brush body minus its facing layer having been positioned back side down, the open sink or well in its face portion is then nearly filled with solidifiable liquid binding material as indicated at 5 31 in Fig. 4. The binding material used should be a solidifiable liquid of low surface tension which will wet the bristles. We have found it most desirable to use a vulcanizable solution of rubber of the kind known commercially as plastic rubber cement and which, as we understand, 10 consists of rubber with suitable amounts of sulphur and an accelerator, in a solvent the boiling point of which is higher than the vulcanizing temperature of the solution. Such a solution is 15 at normal atmospheric temperatures about as fluid as thin molasses, and when subjected to heat of about 240° F. first becomes very fluid and then hardens without disturbing ebullition and without noticeable loss of volume provided it is 20 not subjected to the vulcanizing heat for too long a period. Other materials which will solidify without disturbing ebullition may be used, and we have found especially suitable a solution of an 25 artificial resin of the bakelite type such as the material known as bakelite brush cement.

The template carrying the bristle tufts is brought into position over the layer of liquid rubber solution and moved downward to cause the downwardly extending root ends of the 30 tufts to enter and be immersed in the rubber solution until they strike against the upper surface 32 of the filler block 10. They are then allowed to rest in this position with the weight of the template borne by the bristles the ends of 35 which rest on the filler block. The rubber solution penetrates between the individual bristles of the immersed tuft end portions, and because of its low surface tension and ability to wet the bristles, the solution not only readily enters and 40 fills the spaces between the bristles of the tuft ends but it also rises slightly within each tuft, forming a tapered outwardly curving shoulder 33 about each tuft, which is of advantage in that it gives a more secure anchoring of the tuft in 45 the facing layer of the brush and also facilitates cleaning of the brush.

The rubber solution is introduced into the sink of the brush body in measured quantity gauged to allow for displacement resulting from the immersion of the ends of the tufts, so that when 50 the tuft ends have been immersed the level of the solution will be brought to the desired point on the side of the body shell 12. Instead of first filling the liquid binding material into the sink 55 of the brush body and then moving the ends of the assembled tufts down into the liquid, the assembled tufts might obviously be placed with their ends resting on the bottom of the sink and the binding material thereafter poured into the 60 sink. In both procedures the tuft ends may be considered as being immersed in the liquid binding material, and the term "immerse" is used in the claims with this understanding.

Because of the length of the tuft ends extending 65 downward from the template, the template does not come into contact with the rubber solution or other solidifiable liquid binding material. Adhesion of the template to the face of the brush is thus avoided so that it is free to be stripped 70 off from the bristles of the completed brush. In addition, the weight of the template borne by the immersed bristles serves to maintain the tuft ends in the desired position in the liquid layer and with respect to the brush body. The result- 75 ing pressing of the immersed bristle ends against

the surface of the filling block, which will be more or less according to the weight of the template, is also of advantage in that it tends to emphasize, or at least maintain, the flare or spread condition of the immersed root ends of 5 the tufts which has resulted from the tight packing of the bristles of each tuft into a perforation of the template and the consequent constriction of the tuft at a point distant from its root end greater than the depth to which the end is im- 10 mersed in the liquid.

If adhesive material is, as stated, applied to the root end of the tufts before the second jouncing operation, the material used is desirably but not necessarily one which will dissolve quickly in the 15 liquid binding material of the surface layer. If a solution is used, it should have a readily volatile solvent so that it will set quickly, and in such case, the tuft ends should not be immersed in the facing layer binding material until the solvent 20 of the adhesive material has been allowed to evaporate. Most desirably, and especially if the adhesive material is not readily soluble in the binding material, the adhesive material is applied only to the extreme ends of the bristles, so 25 that a considerable portion of the immersed length of the spaced bristles is left free for penetration of the liquid binding material of the surface layer. If, for example, the surface layer is to be approximately $\frac{1}{4}$ " thick, the adhesive 30 applied to the ends of the tufts should best not extend more than approximately one-third of that distance from the extreme ends of the bristles. Even though the adhesive material is not 35 readily soluble in the binding material, any undissolved adhesive material will be securely embedded in and bound to the surrounding material of the solidified facing layer.

After the bristles and the brush body have been thus assembled with the tuft root ends immersed 40 in the liquid facing layer and abutted against the filling block, and while the tufts are so held, the facing layer is solidified either by letting it stand a sufficient time or by subjecting it to some influence, as determined by the kind of binding material used. If the material is a vulcanizable rubber solution, the assembly is preferably allowed to stand for several hours, usually about 45 6 hours, or more, with the rubber solution referred to, to allow for the escape of pocketed air 50 carried into the rubber solution by the tuft roots. The assembled brush body and bristles are then placed in a vulcanizing chamber and heat-treated for a suitable period, usually, when using the rubber composition referred to, for about 12 hours at 55 a temperature of about 240° F. After removal of the brush from the vulcanizing chamber, the template 15 is removed by withdrawing it over the free ends of the tufts, and the brush is thereafter given any desired finishing operations, such as 60 trimming the outer ends of the tufts to desired form by means of a suitable cutter.

If the brush body does not have a metal or other shell or casing, other means are provided to serve as side walls extending above the surface of the body block to form a sink or open mold for holding the liquid binding material, or a complete open mold no part of which is to form any part of the brush body may be used to form a facing layer with the bristle tufts anchored 65 therein, which may subsequently be attached to a brush back or body piece in any suitable manner.

The spacing of the bristles in the individual tufts at the surface of the facing layer has the 70 effect of increasing the spread of the tufts at their 75

outer ends. Because of this, a desired spreading of the tufts and spacing of the bristles at the working face of the brush may be obtained with the use of shorter or stiffer bristles than when the bristles are closely held together at the surface of the body facing layer, and a further advantage resulting from such spacing of the bristles at the surface of the facing layer is that, without changing the spacing of the tufts or the size of the tufts or the length or stiffness of the bristles, the character of the brush with respect to the distribution of the bristles at the working face of the brush may be varied merely by varying the length to which the inner ends of the tufts are caused to extend beyond the template at the time that the tuft ends are immersed in the binding material and thereby varying the degree of spacing of the bristles at the surface of the body facing layer. The shorter the tuft ends and the closer the template comes to the layer of binding material, the less will the bristles be spaced at the surface of the facing layer, and the less the bristles are spaced at the surface of the facing layer the tighter, or less spread, will the tufts be at their outer ends; and the longer the tuft ends and the farther the template stands off from the layer of binding material, the more the tufts will tend to spread at their outer ends because of the greater spacing of the bristles at the surface of the facing layer. These additional advantages of the new method and the product thereof are of great practical importance.

While the greatest advantage of the invention is obtained when the bristles are arranged in spaced tufts, since the ends of the tufts held and constricted as described are free to expand in all lateral directions, yet much advantage results from use of the new method in making brushes in which the tufts are arranged in spaced rows or other spaced arrangement even though when arranged in rows the bristles extending below the holding and constricting means are free to spread only transversely to the length of the row.

Figs. 8 and 9 illustrate the making of a brush in which the bristles are arranged in spaced rows. As shown, the bristles are arranged in four rows 40 and are constricted and held in the desired arrangement by spacing bars 41 between the rows and an encircling band 42. When it is desired that the openings between the rows of bristles shall be closed at the ends of the brush, the bristles may be arranged to extend about the ends of the bars 41 within the band 42, as shown by Fig. 8. The bristles may be so arranged in spaced rows by the usual hand method. In so arranging the bristles a sufficient quantity should be used so that when enclosed by the band 42 the bristles will be packed fairly tightly between the bars and between the outer bars and the band.

The bars and band, or other bristle-holding means, are positioned at a suitable distance from the butt, or root, end of the bristles greater than the distance to which the root end portions are to be inserted in the binding material, so that the bristles at and near the root ends thereof will spread and be spaced somewhat apart transversely to the length of the row. The thus spread root ends of the bristles are then, as in making a brush with spaced tufts as before described, immersed in a layer of solidifiable liquid binding material such as hereinbefore described, and after the binding material has penetrated into the immersed portions of the rows of bristles between the spaced bristles

thereof, the binding material is solidified, as by vulcanizing when a vulcanizable binding material is used, and thereafter the bristle-holding and constricting means is removed. The bristles on being relieved from the constraint of the holding means will spread somewhat, as indicated by dotted lines in Fig. 9.

As shown by Fig. 9, the body of the brush has no filling block as in Fig. 5, but is composed merely of the layer of binding material 11a 10 filled into a metal shell 12a. The shell 12a may be provided with a suitable number of inwardly projecting studs 43 to be embedded in the binding material 11a so as to insure a strong connection between the layer or body of binding material and the casing. 15

Instead of following the hand method of arranging the bristles in spaced rows and holding them by means of spacing bars and a dummy band as illustrated by Figs. 8 and 9, the bristles 20 may be jounced into a suitable template, such, for example, as the template 15a shown by Fig. 10.

What is claimed is:

1. A brush, comprising a plurality of tufts of 25 single length bristles, and a body having a tuft-holding layer of solidified binding material which forms the face of the body and in which the root end portions of the tufts are embedded and by which they are held, the embedded root 30 portion of the bristles of each tuft extending in the general direction of the length of the tuft and the bristles of each tuft being spaced apart at the surface of and within the facing layer, and the binding material extending into said root portions between individual bristles thereof and the surface of the facing layer curving outwardly about the tufts, whereby the bristles are individually gripped by the binding material and each root portion as a whole is securely anchored 40 in the facing layer.

2. A brush, comprising a plurality of tufts of single length bristles, and a body having a tuft-holding layer of vulcanized rubber composition which forms the face of the body and in which 45 the root end portions of the tufts are embedded and by which they are held, the embedded root portion of the bristles of each tuft extending in the general direction of the length of the tuft and the bristles of each tuft being spaced apart 50 at the surface of the facing layer and diverging from the surface of the facing layer inward, and the rubber composition extending into said root portions between individual bristles thereof and the surface of the facing layer curving outwardly about the tufts, whereby the bristles are 55 individually gripped by the rubber composition and each root portion as a whole is anchored in the facing layer.

3. A brush, comprising a plurality of tufts of 60 single length bristles, and a body portion having a filler block and an enclosing shell the edge portion of which extends beyond the block and a tuft-holding layer of solidified binding material within the extending edge portion of the shell 65 and which forms the face of the body, the root end portions of the tufts being embedded in said facing layer and being held thereby, the embedded root portion of the bristles of each tuft extending in the general direction of the length 70 of the tuft and the bristles of each tuft being spaced apart at the surface of the facing layer and diverging from the surface of the facing layer inward, and the binding material extending into said root portions between individual 75

bristles thereof and the surface of the facing layer curving outwardly about the tufts.

4. A brush, comprising a plurality of spaced assemblages of single length bristles, and a body having a bristle holding layer of solidified binding material which forms the face of the body and in which the root end portions of the bristles are embedded and by which they are held, the embedded root portions of the bristles extending in the general direction of the free portions of the bristles and the bristles of each assemblage being spaced apart in at least one lateral direction at the surface of the facing layer and diverging in at least one such lateral direction from the surface of the facing layer inward, and the binding material extending into the root portions of the assemblages between individual bristles thereof and the surface of the facing layer curving outwardly about the tufts, whereby the bristles are individually gripped by the binding material and the root portion of each assemblage as a whole is securely anchored in the facing layer.

5. A brush, comprising a plurality of spaced rows of single length bristles, and a body having a bristle-holding layer of solidified binding material which forms the face of the body and in which the root end portions of the bristles are embedded and by which they are held, the embedded root portion of the bristles of each row extending in the general direction of the free portions of the bristles and the bristles of each row being spaced apart transversely of the length of the row at the surface of the facing layer and diverging transversely of the length of the row from the surface of the facing layer inward, and the binding material extending into said root portions between individual bristles thereof and the surface of the facing layer curving outwardly about the rows of bristles, whereby the bristles are individually gripped by the binding material and each root portion as a whole is securely anchored in the facing layer.

6. The method of making a brush having spaced tufts of bristles the ends of which are embedded in solidified binding material forming the facing layer of the brush, which comprises immersing the root end portions of the tufts in a layer of liquid binding material in an open face portion of the brush body, the liquid binding material being one which will wet the bristles and which is solidifiable by heat and the boiling point of which is higher than the temperature by which the material is solidified, holding the bristles in position in the binding material with the bristles of each root portion extending downward in the general direction of the length of the tuft and diverging from the outer surface of the binding material inward, and after entrapped air has been allowed to escape from the liquid binding material solidifying the material by subjecting it to heat.

7. The method of making a brush having spaced tufts of bristles the inner ends of which are embedded in solidified binding material, which comprises positioning the tufts in the desired spaced arrangement and constricting them at a point spaced from their inner ends a distance substantially greater than the depth to which the ends are to be embedded in the binding material, whereby the bristles of the inner end portions of the tufts are caused to diverge and to be spaced apart for a distance from their ends greater than the depth to which they are to be embedded in the binding material, immersing the inner end portions of the tufts with their bristles thus

spaced apart in a layer of solidifiable liquid binding material which will wet the bristles, and solidifying the binding material after it has entered into the end portions of the tufts between the spaced bristles thereof.

8. The method of making a brush having spaced tufts of bristles the inner ends of which are embedded in a facing layer of solidified binding material, which comprises positioning the tufts in the desired spaced arrangement in a template whereby the tufts are constricted at a point spaced from their inner ends a distance substantially greater than the depth to which the ends are to be embedded in the binding material, whereby the bristles of the inner end portions of the tufts are caused to diverge and to be spaced apart for a distance from their ends greater than the depth to which they are to be embedded in the binding material, immersing the inner end portions of the tufts with their bristles thus spaced apart in a layer of a liquid binding material in an open container, the liquid material being one which will wet the bristles and which is solidifiable substantially without loss of volume, solidifying the binding material while the tufts are held in position by the weight of the template with their bristle ends resting on the bottom of the container, and thereafter removing the template.

9. The method of making a brush having spaced tufts of bristles the inner ends of which are embedded in a facing layer of solidified binding material, which comprises positioning the tufts in the desired spaced arrangement in a template whereby the tufts are constricted at a point spaced from their inner ends and the bristles of the inner end portions of the tufts are caused to diverge, immersing the inner end portions of the tufts with their bristles thus spaced apart in a layer of a solidifiable liquid binding material in an open container by moving the tuft-carrying template downward to project the tuft ends into the liquid and against the bottom of the container, solidifying the binding material while the tufts are held in position by the weight of the template with their bristle ends resting on the bottom of the container, and thereafter removing the template.

10. The method of making a brush having spaced tufts of bristles the inner ends of which are embedded in solidified binding material, which comprises positioning the tufts in the desired spaced arrangement in a template whereby the tufts are constricted at a point spaced from their inner ends and the bristles of the inner end portions of the tufts are caused to diverge, applying adhesive material to the ends of the bristles of the inner end portions of the tufts, immersing the inner end portions of the tufts in a layer of a solidifiable liquid binding material which will wet the bristles, solidifying the binding material after it has entered into the end portions of the tufts between the spaced bristles thereof above adhesive material on the ends of the bristles, and thereafter removing the template.

11. The method of making a brush having spaced assemblages of bristles the inner ends of which are embedded in solidified binding material, which comprises positioning the bristles in the desired arrangement and holding and constricting them at a point spaced from their inner ends a distance greater than the depth to which the ends are to be embedded in the binding material, whereby the inner end portions of the

5 bristles of each assemblage are caused to diverge and to be relatively loosely grouped, immersing the inner end portions of the bristles thus loosely grouped in a layer of solidifiable binding material which will wet the bristles, and solidifying the binding material after it has entered between the end portions of the loosely grouped bristles.

10 12. The method of making a brush having spaced rows of bristles the inner ends of which are embedded in a facing layer of solidified binding material, which comprises positioning the bristles in the desired arrangement of spaced rows and holding and constricting them at a point spaced from their inner ends a distance

substantially greater than the depth to which the ends are to be embedded in the binding material, whereby the inner end portions of the bristles of each row are caused to diverge transversely of the length of the row, immersing the inner end portions of the bristles while the rows are thus held and constricted in a layer of solidifiable binding material which will wet the bristles, and solidifying the binding material after it has entered into the immersed portions of the rows between the laterally spaced bristles thereof.

ERNEST B. WRIGHT, JR., ET AL.

It is hereby certified that error appears in the printed specification of the above numbered patent requiring correction as follows: Page 5, first column, line 19, claim 4, for "tufts" read assemblages; and that the said Letters Patent should be read with this correction therein that the same may conform to the record of the case in the Patent Office.

Signed and sealed this 29th day of June, A. D. 1937.

Henry Van Arsdale

Acting Commissioner of Patents.

(Seal)

5 bristles of each assemblage are caused to diverge and to be relatively loosely grouped, immersing the inner end portions of the bristles thus loosely grouped in a layer of solidifiable binding material which will wet the bristles, and solidifying the binding material after it has entered between the end portions of the loosely grouped bristles.

10 12. The method of making a brush having spaced rows of bristles the inner ends of which are embedded in a facing layer of solidified binding material, which comprises positioning the bristles in the desired arrangement of spaced rows and holding and constricting them at a point spaced from their inner ends a distance

substantially greater than the depth to which the ends are to be embedded in the binding material, whereby the inner end portions of the bristles of each row are caused to diverge transversely of the length of the row, immersing the inner end portions of the bristles while the rows are thus held and constricted in a layer of solidifiable binding material which will wet the bristles, and solidifying the binding material after it has entered into the immersed portions of the rows between the laterally spaced bristles thereof.

April 27, 1937.

ERNEST B. WRIGHT, JR., ET AL.

It is hereby certified that error appears in the printed specification of the above numbered patent requiring correction as follows: Page 5, first column, line 19, claim 4, for "tufts" read assemblages; and that the said Letters Patent should be read with this correction therein that the same may conform to the record of the case in the Patent Office.

Signed and sealed this 29th day of June, A. D. 1937.

Henry Van Arsdale

Acting Commissioner of Patents.

(Seal)

CERTIFICATE OF CORRECTION.

Patent No. 2,078,358.

April 27, 1937.

ERNEST B. WRIGHT, JR., ET AL.
